UNITED STATES PATENT OFFICE.

GEORGE EDWIN BILTON, OF TORONTO, ONTARIO, CANADA, ASSIGNOR OF ONE-HALF TO
NORMAN CECIL MAYNARD, OF TORONTO, ONTARIO, CANADA.

TRAY.

1,221,788.

Specification of Letters Patent.

Patented Apr. 3, 1917.

Application filed May 18, 1916. Serial No. 98,474.

To all whom it may concern:

Be it known that I, GEORGE EDWIN BILTON, a subject of the King of Great Britain, and resident of 14 Bloomfield avenue, in 5 the city of Toronto, county of York, Province of Ontario, Dominion of Canada, have invented certain new and useful Improvements in Trays, of which the following is a specification.

10 The invention relates to improvements in trays as described in the present specification and shown in the accompanying drawings that form part of the same.

The invention consists essentially of the 15 novel construction and arrangement of parts whereby legs hingedly secured to the under-side of the tray are adapted, through the operation of the tray handles, to fold inwardly flat against said tray or to extend at 20 right angles thereto to form supports for said tray.

The objects of the invention are to provide a supporting means which may be readily folded out of the way, to facilitate transportation, to provide a tray, the operating mechanism of which is entirely concealed from view when the legs are collapsed and generally to provide a simple, durable and efficient tray.

30 In the drawings, Figure 1 is a perspective view of the tray showing the legs extended and supporting said tray.

Fig. 2 is a view of the bottom of the tray with the legs in their folded positions.

35 Fig. 3 is a longitudinal sectional view through one end of the tray showing the position taken by the operating levers when the legs are extended.

Fig. 4 is a longitudinal sectional view 40 through one end of the tray showing the position taken by the operating levers when the legs are folded.

Fig. 5 is a view of the underside of the 45 central portion of one end of the tray showing the means for locking the legs in their extended positions and the releasing means.

Like numerals of reference indicate corresponding parts in each figure.

Referring to the drawings 1 is the tray 50 top of substantially rectangular shape and having the frame 2 extending therearound, said frame being adapted to project above said top to form a rail for the protection of

the contents and to extend downwardly a sufficient distance to conceal from view the 55 legs and their operating mechanism when said legs are folded.

3 are transverse wooden strips secured to the under side of the top 1 adjacent to each end thereof and forming brackets to which 60 are secured the transverse leg supports 4 by means of the hinges 5, said supports being positioned a sufficient distance from said frame so that when turned backwardly on said hinges their outer sides will abut the 65 said frame.

6 are legs rigidly secured in pairs to the supports 4 said legs being so positioned on said supports that the legs from one support will fold between the legs of the other 70 support.

7 are metal plates countersunk in the leg supports 4 intermediate of the length of said supports and having their ends 8 projecting outwardly past the edges of said supports 75 for receiving pressure to hold said legs supports tightly in engagement with the frame 2.

9 are wooden blocks rigidly secured to the under side of the tray 1 adjacent to the 80 strips 3.

10 are flat metal springs secured to the blocks 9 by the straps 11 and having their ends 12 extending outwardly in substantially arc shape and adapted to abut the projecting ends 8 of the plates 9 to hold them rigid with the frame 2.

13 are spring releasing plates loosely mounted on the sides 14 of the leg supports 4 and slotted as at 15 to accommodate the 90 plates 7 and the outer ends 12 of the springs 10, said plates having their ends bent at right angles and curved outwardly over the edges of the supports 4 and forming the lever handles 16 for raising said plates 13 to 95 force the springs 10 from engagement with the plates 7 to allow the legs 6 to proceed to their folded positions.

17 are metal handle brackets secured to the ends of the frame 2 and supporting at 100 their outer ends the wooden grips 18 rotatably mounted therein, said brackets being slotted on the under side to accommodate the leg operating levers.

19 are metal rods extending longitudinally through the grips 18 and being rota-

table therewith, said rods being substantially square in cross section and having rigidly secured thereto within the brackets 17 the levers 20, said levers being curved correspondingly to the brackets 17 and operating within the slotted portions of said brackets.

21 are links pivotally connecting the lower ends of the levers 20 with the lever handles 16 and operating in the slots 22 through the frame 2 and completing the connections between the spring releasing plates 13 and the handles or grips 18 for operating the legs.

When the legs 6 are extended and it is required to bring them to their folded positions the tray is lifted by means of the handles or grips 18 and said grips are then turned by a slight inward pressure of the wrist of the operator thus forcing the lower ends of the levers 20 inwardly and causing the links 21 to press on the lever handles 16 and as the plates 13 are but loosely secured to the leg supports 4 this pressure on the handles 16 causes the said plates 7 to force the ends of the springs 10 out of engagement with the plates 7 and allows the legs to slide along the curved portions of said springs to their positions against the tray top where they are held by the pressure of the said springs against the said leg supports.

It will be seen that when the legs are in the folded positions the levers 20 enter the slots in the brackets 17 and the tray assumes the appearance of an ordinary tray.

To bring the legs to their extended positions the grips 18 are turned by a slight outward pressure of the wrists of the operator causing the links 21, 20 and 16 to draw the leg supports 4 along the springs 13 and into engagement with the frame 2 where they are rigidly held by the pressure of the said springs against the projecting ends of the plates 7.

45 What I claim is:

1. In a tray, a frame, a top secured to said frame, a plurality of legs rigidly connected by cross bars and hinged to said tray in sets, spring latch mechanisms for maintaining said legs in their extended positions, members adapted to depress the springs of said latches and disengage them from their fastenings and toggle-joint mechanism operatively connected with said members.

2. In a tray, a frame, a top secured to said frame, folding legs secured under said top, spring latch mechanism for maintaining said legs in their extended positions, latch opening members, toggle-joints pivotally connected to said opening members and tray handles having rotative members rigidly secured to the toggle joint sections.

3. A tray, a frame extending downwardly from said tray, transverse leg supports

hinged to the under side of said tray and carrying legs and swinging outwardly against said frame, spring members locking said leg supports to said frame, releasing members secured to said leg supports and slotted to receive said springs, handle brackets secured to the tray ends, grips rotatably mounted in said brackets and having arms rigid therewith and extending downwardly therefrom and links joining said arms to said releasing members.

4. A tray, a frame extending downwardly from said tray, transverse leg supports hinged to the under side of said tray and carrying legs and swinging outwardly against said frame, spring members secured to the underside of said tray and locking said leg supports to said frame when said legs are in their upright positions, releasing plates loosely mounted on said leg supports and slotted to receive said springs, levers connected to said plates, handle brackets secured to the tray ends, grips rotatably mounted in said brackets and having arms rigid therewith and extending downwardly therefrom and links joining said arms to said levers.

5. A tray, a frame extending downwardly from said tray, transverse leg supports hingedly secured to the under side of said tray and carrying legs, spring members secured to the under side of said tray and holding said legs to their upright positions, releasing plates loosely mounted on said leg supports and engaging said springs, curved lugs extending outwardly from said releasing plates and projecting beyond the edges of said leg supports, lever handles, and links pivotally connecting said lever handles and said lugs.

6. A tray, a frame extending downwardly from said tray, transverse leg supports hingedly secured to the under side of said tray and carrying legs, spring members secured to the under side of said tray and holding said legs to their upright positions, releasing plates loosely mounted on said leg supports and engaging said springs, curved lugs extending outwardly from said releasing plates and projecting beyond the edges of said leg supports, handle brackets rigidly secured to the tray ends, shafts rotatably mounted in said brackets and carrying grips rotatable therewith, and having arms rigidly secured thereto and extending downwardly and links connecting said arms to said lugs.

7. A tray, a frame extending downwardly from said tray, transverse leg supports hingedly secured to the under side of said tray and carrying legs, spring members secured to the under side of said tray and holding said legs to their upright positions, releasing plates loosely mounted on said leg supports and engaging said springs, curved lugs extending outwardly from said releasing

plates and projecting beyond the edges of said leg supports, handle brackets rigidly secured to the tray ends, said brackets being slotted longitudinally on their outside edges, shafts rotatably mounted in said brackets and carrying grips rotatable therewith, and having arms rigidly secured thereto and adapted to enter said slots when the legs are

in the collapsed positions, and links connecting said arms to said lugs.

10

Signed at the city of Toronto, Province of Ontario, this third day of May 1916.

GEORGE EDWIN BILTON.
